UNITED STATES PATENT OFFICE.

ELMER A. SPERRY, OF CLEVELAND, OHIO, ASSIGNOR, BY MESNE ASSIGNMENTS, TO AMERICAN ELECTRIC AND CONTROLLER COMPANY, A CORPORATION OF DELAWARE.

SYSTEM OF POWER TRANSMISSION.

1,136,058.

Specification of Letters Patent. Patented Apr. 20, 1915.

Application filed March 9, 1903. Serial No. 147,028.

To all whom it may concern:

Be it known that I, ELMER A. SPERRY, a citizen of the United States, residing at Cleveland, in the State of Ohio, have invented certain new and useful Improvements in Systems of Power Transmission, of which the following is a specification, accompanied by drawings.

My invention relates to systems of power transmission, more particularly to systems for the electrical transmission of power; and the object of my invention is to improve upon such apparatus for this purpose, whereby translating devices may be readily 15 and efficiently controlled, and power transmitted thereto by improved means.

Further objects of my invention will hereinafter appear, and to these ends my invention consists in circuits and apparatus for carrying out the above objects, constructed and arranged and having the general mode of operation substantially as hereinafter fully described and shown in this specification and accompanying drawings in which—

25 Figure 1 is a vertical sectional view of apparatus embodying my invention; Fig. 2 is a transverse sectional view on the line $x-x$ of Fig. 1; Fig. 3 is an outside elevation of the apparatus; and Fig. 4 is a diagrammatic view of circuits and apparatus embodied in my invention.

Referring to the drawings, in Fig. 1 the construction of an interrupter is fully shown which may be used in connection with my 35 improved system of power transmission, although any suitable form of interrupter or circuit making and breaking device may be used whereby the circuit may be rapidly made and broken.

40 In the form of device illustrated in Fig. 1 and in the other drawings, the circuit making and breaking device is shown inclosed within a suitable casing B which may be a conductor and utilized to form one terminal 45 of the circuit leading to the interrupter. Within the casing solid conductors C and fluid conductors are shown movable relatively to each other, in this instance the apparatus for utilizing a fluid as a conductor being rotatable relatively to the solid conductors C, this apparatus being shown in the form of one or more nozzles F with provision for forcing a conducting fluid therefrom upon the interior surfaces of the conductor C which may conveniently be ar-

ranged in the form of substantially cylindrical plates having points D whereby non-conducting intervals are provided on the conducting portions of the plates.

The construction of the apparatus described is suitable and convenient for the ends in view, and as shown a central shaft G is provided with a bearing K at the bottom of the casing within a liquid receptacle E, while another bearing is provided for the shaft within the cover L of the apparatus, an insulating plug M being shown surrounding the shaft to insulate it from the casing. Connected to the shaft are means for raising the conducting fluid which may be contained in the receptacle, this means being shown as a screw-threaded conveyor H adapted to rotate with said shaft G while the nozzles F are adjustably connected as by means of set screws Q to the rotary shaft G. The conductors C are adjustable relatively to the nozzles and are suitably supported upon insulated plates T and U, which plates are connected to each other by suitable rods W provided with insulating sleeves Y, and these plates and conductors may be raised or lowered by means of a screw-threaded rod Z suitably secured in the cover L and provided with a handle b for rotating the same, so that rotation of the rod Z will cause the plate U to move upwardly and downwardly on the screw-threaded portion of the rod. A guide rod c connected to the plate U passes slidably through the cover L.

In the operation of the device, rotation being imparted to the central shaft G and suitable electrical connections being made as hereinafter to be described, the liquid contained in the receptacle E will be carried upwardly by the conveyor H through pipe I to the lower nozzle F and through the aperture O in said nozzle, and pipe J to the upper nozzle F, the liquid being forced outwardly from said nozzles by centrifugal action in the form of continuous streams which impinge upon the conductors C, thereby completing circuit thereto. By raising and lowering the conductors C as described, it will be seen that the duration of the contact of the stream upon the conductors may be varied for longer or shorter portions of the time during which the stream or streams of conducting fluid will impinge upon the

conductors C in the rotation of the apparatus will be varied. When the apparatus is connected in circuit with the motor, the current of which circuit is to be interrupted by the apparatus, and which motor is to in turn drive the apparatus, in order to start the same some means must be provided for giving an initial impulse to the apparatus to cause the initial flow of conducting fluid, in order that the circuit to the motor may be initially completed and the motor started, and when it is started the motor will then continue to drive the interrupter. In order that an initial impulse may be given to the apparatus for forcing a stream of fluid upon the conductor, any suitable means may be provided, but in this instance I have shown a pinion 1 on the shaft G and a segmental rack 2 connected to a slotted arm 3 pivoted on the plate L at 4, and normally held against the stop 5 by a suitable spring 6. In order to start the apparatus, the handle 7 is swung about the pivot 4, thereby carrying the segmental rack 2 into engagement with the pinion 1, and by sweeping said rack past said pinion an initial rotary motion or spin will be given to the shaft G, thereby starting the flow of conducting fluid and causing it to impinge upon the conductor or conductors C to complete the circuit to the motor after which, it being assumed that the motor is connected to drive the apparatus as shown in Figs. 1 and 4, the interrupter will be operated by the rotation of the motor. The slotted spring pressed arm 3 may be drawn outwardly so that the rack will not engage the pinion when the arm 3 is returned to the position shown, the slot permitting such movement of the arm. Means are provided for leading circuit wires to the interrupter at suitable points, as shown the circuit wires being preferably led through apertures in the casing B to contact screws on the conductor C, and means are also provided for leading a conducting wire to the casing B which as stated is in circuit with the fluid conductor. Any suitable conducting fluid or liquid may be used, mercury having been found suitable as a liquid.

Referring more particularly to Fig. 4, G' represents a suitable generator or source of supply for electric current, of which 8 represents the field winding, and while there may be any suitable number of such generators connected in circuit, I have shown but one, the circuit being branched from one of the brushes of the generator, and the circuit comprising three branches 9, 10 and 11, between two of which, as 10 and 11, suitable lights may be connected as well as the field windings 12 and 13 of the motors 14, the armature circuits of which are connected between the points 15 and 16, and 17 and 18 respectively on the wires 9 and 10, so that it

will be seen that the field windings 12 and 13 derive their energy from separate circuits from those which supply current to the armatures of the motors 14. It will be understood that there may be any number of 70 motors or other translating devices connected as described, and taking the circuits of one motor it will be seen that a current interrupter which will be designated as B is connected in circuit with the armature of 75 the motor together with a starting rheostat 19, while a suitable condenser *i* is connected to reduce sparking at the interrupter. In the present instance I have shown the interrupter as operated by the motor, in the armature circuit of which is included the interrupter, and I have also shown an additional starting device for this motor, independent of the circuit of the interrupter itself. Further, I provide mechanical connections between the motor and the interrupter whereby the periodicity of the action of the interrupter can be varied. As shown in Figs. 1 and 4, the motor shaft 20 is provided with a friction disk 21 engaging with a friction 90 disk 22 carried by the shaft G of the interrupter, and means are provided for moving the disk 22 across the disk 21 whereby the shaft G may be driven at variable speeds, and the speed of rotation of the nozzles F 95 carried by the shaft G may be varied independently of the speed of the motor which may be a variable speed motor. As shown, the disk 22 is provided with a clutch member 23 adapted to engage with a clutch member 24 rotatable with the shaft G by means of a groove 25 and internal feather on member 24. Said clutch member 24 is movable longitudinally of the shaft G as is the disk 22 and clutch member 23, and suitable means 100 are provided for raising and lowering the member 24, as shown there being a spring-pressed arm 26 pivoted at 27 and provided at one end with a handle 28, while at the other end the arm is pivotally connected at 110 29 to a ring 30 loosely encircling the member 24, so that the clutch members and disk 22 may rotate but may be slid longitudinally along the shaft G.

In order that the disk 22 may be maintained in any given position on the shaft longitudinally of the same, any suitable means may be provided. In this instance the weight of the parts of the clutch is approximately balanced by a spring 26^a and 120 the friction of the various bearings, as for instance at the pivot 27, is made of such amount that a suitable amount of force is necessary to move the parts from any position in which they are placed. When the 125 apparatus is to be started, the clutch member 24 may be moved downwardly out of engagement with the clutch member 23 and an initial impulse be given to the shaft G and nozzles F by means of the starting de- 130

vice hereinbefore described. The member 24 being unclutched from the member 22, only sufficient force is necessary for the initial impulse to set the interrupter in rotation. If this unclutching had not been effected, sufficient force would be required not only to set the interrupter in rotation, but also to start the motor 14 through the friction members 21 and 22. The member 22 is prevented from following the member 24 in its downward movement by its friction against the disk 21 which just before starting is stationary. The interrupter having been set in rotation, the clutch member 24

10 may be drawn upwardly into engagement with the member 23 and the motor being started, as will be hereinafter described, rotation of the interrupter will be maintained.

When the motor connected as shown is to be operated as a constant speed motor and it is desired to preserve the relations of the speed of the motor and that of the interrupter, or in other words, preserve the periodicity of the action of the interrupter, 20 the clutch members and the wheel 22 may be adjusted in any desired relation to the disk 21 and be retained in this relation by means of the set screw 31.

Various ways of starting the motor may be used and I have shown an electric starting device for the motor which is independent of the circuit of the interrupter and have utilized a rheostat 19 and circuits connected therewith, as shown, the operation of 30 which will now be described. The current passes by means of wire 32 to contact arm 33 of rheostat 19, and assuming that contact arm 33 is resting upon one of the contacts 34, current will pass through the resistance 40 35 and by wire 36 to and through the motor, and from thence to the negative lead and back to the generator G'. The motor will then start up and the clutch member 24 being thrown into engagement with the clutch 45 member 23, rotation will be imparted to the interrupter, whereby contact will be made between the continuous stream of fluid ejected from the nozzles and the conductor C. It is then desirable to exclude the rheostat 19 from the circuit, and the arm 33 is moved across contacts 34 to rest upon insulated contact 37, whereby current will then pass from wire 32 by wire 38 to one of the conductors C of the interrupter, while current will also pass by means of a branch 55 wire 39 to the other conductor C of the interrupter, circuit being completed from thence by means of the fluid to the casing B and by a wire 40 to the point 41 on wire 36, the circuit being completed from thence through the armature of the motor and to the negative lead. The condenser i is shown connected across the interrupter in such manner as to counteract the effects of inductance in 60 the circuit and reduce sparking.

The greatest inductance being in the field of a motor, it will be seen that it is preferable to place the interrupter as shown in Fig. 4, in series with the armature, and the condenser being connected across the interrupter 70 greatly reduces sparking by the usual action of balancing the inductance of the armature. The condenser it will be seen balances not only the inductance of the motor armature, but also that portion of the inductance of 75 the generator armature G' which its fluctuations affect. Inasmuch as the balance for a given condenser on to a given inductance is a factor of its periodicity, it is desirable to have the periodicity constant with a constant condenser, and as according to the construction shown the interrupter is operated from the shaft of a variable speed motor, the variable speed transmission gear is provided varying the periodicity of the interrupter; in other words, the motor speed may be varied as desired, but the periodicity of the interrupter may always be thrown into step with the condenser to reduce sparking. It will also be seen that according to the 80 arrangements of circuits and apparatus as shown, the circuit of the armature of the motor may be rapidly made and broken to regulate and control the current, while the field circuit is maintained intact and is not 85 broken, for the field circuit is connected as shown to the leads of the lighting circuit, while the armature is connected to the power circuit.

It will be seen among other things that 100 with the arrangement shown the motor can be started by manually operating the interrupter so as to close the circuit of the armature of the motor, which motor after it has started, automatically operates the interrupter. Again the motor may be started by the use of a separate or branch circuit including a starting rheostat and switch, and after the motor is thus started, the rheostat is cut out of circuit. By adjusting the relation between the conductors and nozzles of the interrupter, the duration of contact of the make relative to the break in the circuit may be varied. So, too, by adjusting the connection between the driving motor, which 105 in the case shown is the translating device to which current is supplied, and the interrupter, the periodicity of the make and break device may be controlled.

Obviously some features of my invention 120 may be used without others, and my invention may be embodied in widely varying forms, therefore without limiting myself to the construction shown and described nor enumerating equivalents, I claim and desire 125 to obtain by Letters Patent the following:

1. The combination with a motor, of an interrupter connected in circuit with the armature only of the motor for rapidly and continuously making and breaking the circuit 130

thereof while said interrupter is active and operated by said motor, means for increasing and decreasing the duration of the make relative to the break in the circuit of said armature, and a capacity connected to counteract the effects of the inductance of the circuit, substantially as set forth.

2. The combination of a motor, an interrupter constructed to be connected in circuit therewith, a starting rheostat, and circuits and connections for starting the motor with the rheostat in circuit and for then excluding the rheostat from the circuit and operatively placing the interrupter in circuit, and means for reducing sparking at the interrupter, substantially as set forth.

3. The combination of a motor, a device constructed to rapidly make and break the armature circuit without breaking the field circuit, and means for starting the motor without including the make and break device in circuit and for then operatively placing the same in circuit, substantially as set forth.

4. The combination with a motor, of a device connected to rapidly make and break the armature circuit of said motor at all times during the operation of said motor, means for driving said make and break device from the motor, and means for increasing and decreasing the periodicity of the make and break device without change in the speed of the motor, substantially as set forth.

5. The combination of a variable speed motor, a rotary make and break device included in circuit therewith and connected to be driven by the motor, a capacity connected to reduce sparking at the make and break device, and means for varying the periodicity of said device independently of the speed of the motor, substantially as set forth.

6. The combination of a variable speed motor, a rotary circuit interrupter connected in series with the armature and driven by the motor, a condenser connected to reduce sparking at the interrupter, and means for throwing the interrupter into step with the condenser irrespective of the speed of the motor, substantially as set forth.

7. The combination of a variable speed motor, an interrupter in circuit therewith and driven thereby, a capacity connected across the interrupter, and means for varying the periodicity of the interrupter to accord with that of the condenser, substantially as set forth.

8. The combination of a motor, a circuit interrupter and a rheostat, and means whereby the current is first switched to the motor through the rheostat and then through the interrupter, substantially as set forth.

9. The combination of a motor, a circuit interrupter and a rheostat, and circuits and connections whereby the current is first

switched to the motor around the interrupter and through the rheostat and then the rheostat is cut out of circuit and current passes through the interrupter, substantially as set forth.

10. The combination of a variable speed motor, a rotary interrupter connected to be driven by the motor and included in the motor circuit, and variable speed gearing between the motor and the interrupter, whereby the periodicity of the interrupter may be varied, and a capacity for reducing sparking at the interrupter, substantially as set forth.

11. In a device of the class described, the combination with a translating device adapted to be connected in circuit with a source of current supply, of means in said circuit and actuated by said device for rapidly making and breaking the circuit of the translating device while the latter operates including a container adapted to contain a conducting fluid, said fluid and container constituting a part of the circuit.

12. In a system of electrical transmission of power, the combination with a source of supply, of two circuits leading therefrom, a motor the field magnet of which is in one circuit and the armature of which is in the other circuit, means operated by said motor for continuously interrupting the armature circuit, said field circuit being independent of the interrupting means, and means for varying the periodicity of said interrupter, substantially as set forth.

13. In a system of electrical transmission of power, the combination with a source of supply, of two circuits leading therefrom, a motor the field magnet of which is in one circuit and the armature of which is in the other circuit, means for interrupting the armature circuit, said field circuit being independent of said interrupting means, means for increasing and decreasing the duration of the make relative to the break in said armature circuit, and means for varying the periodicity of said interrupter, substantially as set forth.

14. The combination of a variable speed motor, a circuit interrupter connected in circuit therewith and connected to be driven by the motor, means for varying the speed of the interrupter without variation in the speed of the motor, said interrupter comprising a conductor having non-conducting intervals and apparatus for forcing a continuous stream of conducting fluid on said conductor, substantially as set forth.

15. The combination of a variable speed motor, a circuit interrupter connected in circuit therewith and connected to be driven by the motor, means for varying the speed of the interrupter without variation in the speed of the motor, said interrupter comprising a conductor having non-conducting

intervals and apparatus for forcing a continuous stream of conducting fluid on said conductor, and means for counteracting the inductance of the circuit, substantially as set forth.

16. The combination of a variable speed motor, a circuit interrupter connected in circuit therewith and connected to be driven by the motor, said interrupter comprising a conductor having non-conducting intervals and apparatus for forcing a continuous stream of conducting fluid on said conductor, means for counteracting the inductance of the circuit, and means for varying the periodicity of the interrupter independently of the speed of the motor, substantially as set forth.

17. The combination of a motor, an interrupter connected to be operated thereby and adapted to regulate the motor, said interrupter comprising a single, annular conductor having tapering non-conducting intervals and a pumping device for causing a stream of conducting fluid to impinge upon said conductor when the motor is rotating, said conductor and pumping device being revoluble relatively to each other, substantially as set forth.

18. The combination of a motor, an interrupter for the circuit thereof, a con-

denser connected to reduce sparking at the interrupter, and means for varying the periodicity of the interrupter to accord with the highest efficiency of the condenser, substantially as set forth.

19. In a system of electrical transmission of power, the combination with a source of supply, of a pair of conductors connected to one pole thereof and extending to a distance therefrom, a third conductor connected to the other pole and constituting a common return for each of said first named conductors, a motor having its armature connected between one of said conductors and common return, and means for rapidly and continuously interrupting such armature circuit, the field of said motor being connected across the other of said conductors and common return, whereby variations of current in the armature circuit will exert a minimum disturbing effect on the field circuit.

In testimony whereof I have signed my name to this specification in the presence of two subscribing witnesses.

ELMER A. SPERRY.
